FOOT EXERCISING MACHINE

Charles C. Moshier, Bethany, Ohio

Application August 11, 1948; Serial No. 43,712

7 Claims. (Cl. 128—25)

1

My invention relates to a foot exercising machine. It has to do, more particularly, with a foot exercising machine of the general type illustrated in my Patents No. 2,376,000 of May 15, 1945 and No. 2,397,428 of March 26, 1946. The present invention is directed to important improvements over the machine disclosed in said patents.

The machine disclosed in my prior patents was adapted to subject the front portion of the foot to a circular movement while holding the rear portion of the foot in a relatively fixed position in order to exercise the joints of the foot, ligaments, muscles and fascia around the joints so as to assist in maintaining proper blood circulation and to help to relieve nerve pressure.

The present machine is provided for the same purpose but accomplishes this purpose in a more natural and beneficial way. With the machine disclosed herein, the same gentle and beneficial treatment can be given which formerly could be given only by the hands and fingers of the highly skilled technician, after many years of training and experience.

According to the present invention, the forward portion of the foot is moved through a circular path, the direction of movement being reversed at intervals. Instead of supporting the rear portion of the foot in a relatively fixed position during the circular movement of the forward portion of the foot, the heel portion or rear portion is unsupported and, consequently, a more natural manipulation of the foot can be obtained. The circular motion imparted to the toe members or front portion of the foot will necessarily flex the mid-portion of the foot and also create a slight longitudinal action between the toes and the metatarsal joint of the foot. In addition to the manipulation of the front portion of the foot, the main arch portion is subjected to a kneading action. This is accomplished by subjecting the arch to a rolling action which relieves pressure thereon. The machine of this invention will manipulate both feet at once and, in this respect, differs from my prior machine which was designed to act on one foot at a time. The driving and actuating means of the present invention are entirely different from and more efficient than those provided in my prior machine.

The preferred embodiment of my invention is illustrated in the accompanying drawings wherein similar characters of reference designate corresponding parts and wherein:

Figure 1 is a perspective view, partly broken away, of a machine made according to my invention.

2

Figure 2 is a view, partly in top plan and partly in horizontal section, of the machine of Figure 1.

Figure 3 is a vertical sectional view taken substantially along line 3—3 of Figure 2.

Figure 4 is a vertical sectional view taken substantially along line 4—4 of Figure 2 at right angles to that of Figure 3.

Figure 5 is a similar sectional view but taken substantially along line 5—5 of Figure 2.

Figure 6 is an enlarged schematic view illustrating how the foot is supported by my machine.

Figure 7 is a schematic view illustrating how the foot is manipulated by my machine.

With reference to the drawings, in Figure 1 I have illustrated my machine as including a supporting base plate 1 over which a housing 2 is slipped and which is secured thereto by means of bolts 3. The housing 2 is provided with an upstanding rear portion 4 and a lower forward portion 5.

Mounted on the base plate 1 within the housing, as shown best in Figures 2 and 5, is an electric driving motor 6. This motor 6 drives a gear unit 7 extending from one side of the motor, it being noted that the motor is disposed within the portion 4 of the housing at one corner thereof. The gear unit 7 drives a forwardly extending shaft 8 to which it is coupled by a suitable coupling 9. The shaft of the unit 7 has a sprocket 10 and an adjacent gear 11 keyed thereon.

The shaft 8 extends through the forward wall of housing portion 4 into an upstanding worm housing 12 which is supported on the base plate 1.

Within the housing 12, the shaft 8 carries a worm 13 which meshes with a worm gear 14 mounted for rotation about the axis of the vertical shaft 15 to which it is keyed. The shaft 15 extends upwardly through the top of the housing 12 (Figure 3) and has keyed on its upper end a crank 16. The outer end of the crank 16 carries a roller 17 which operates within a slot 18 formed in an actuating arm 19. It will be noted from Figure 2, that the shaft 15 is substantially midway of the sides of the housing. It will be evident from Figures 2 and 3, that the outer end of crank 16 is also connected by the supporting pin 20 of the roller 17 to the rear end of an actuating arm 21. This arm 21 extends forwardly

beneath the upper wall 22 of the forward portion 5 of the housing and in spaced relationship thereto. As shown in Figure 2, the forward end of this arm is provided with a loop portion 23. The extreme forward end of the arm is provided with a depending pivot-bearing 24 (Figure 3).

55

which receives a pivot pin that connects the forward end of arm 21 to the forward end of a slide-supporting bracket 25. This bracket 25 extends rearwardly for a substantial distance beyond the loop portion 23 and beneath the arm 21 in parallel relationship thereto.

Upon the bracket 25 there is mounted a slide block 26, it being evident from Figure 1 that the upper portion of the block is provided with a guide 27 for slidably receiving the bracket 25. The bracket 25 is provided with a longitudinal slot 28 and a clamping screw 29 has its lower reduced end passed through this slot and threaded into the block 26. Thus, when the upperstanding screw 29 is properly rotated, the block 26 can be clamped to the bracket 25 or be released therefrom so that the block 26 can be adjusted along the bracket.

The lower part of the block 26 is provided with a notch for receiving a transverse horizontally disposed rod 29a which is clamped thereto by means of a clamping plate 30. Mounted on the opposite ends of this rod 29 are the upstanding bracket units 31 which support the arch-contacting rollers 32. Each bracket 31 comprises a pair of upstanding arms 33 which are rigidly secured together by the lower cross members 34. At the outer and lower side of each of these bracket units 31 is a vertically disposed plate 35 rigidly secured thereto. This plate 35 supports the guide rollers 36 which are mounted on vertical axes and the guide rollers 37 which are mounted on horizontal axes. The rollers 36 and 37 extend into the track channels 38 which are carried by the base plate 1 adjacent each edge thereof and extend forwardly and rearwardly thereof for a substantial distance adjacent the forward portion of the machine, as shown best in Figure 2. The rollers 36 take any lateral thrust and the rollers 37 take any downward thrust. The upper ends of arms 33 are provided with notches 39 for receiving the projecting roller shafts 40. The rollers 32 are preferably formed with a sponge rubber cover. It will be noted that the screw 29 extends upwardly through a longitudinal slot 42 (Figure 1) provided in the upper wall 22 of housing portion 5. Furthermore, it will be noted that the bracket arms 33 extend upwardly through the forwardly and rearwardly extending slots 43 formed in the top wall 22. This will permit forward and rearward movement of the block 26 which carries the bracket units 31 that support the arch-contacting rollers 32. Furthermore, the slot 42 will permit the adjustment of block 26 on the bracket 25. Since the loop portion 23 is provided on arm 21, free movement of the screw 29 back and forth is permitted when adjusting the block 26 relative to bracket 25.

It will be evident that when the crank arm 16 is rotated about the axis of shaft 15, the actuating arm 21 will be reciprocated forwardly and rearwardly. This will move the entire unit, carried by block 26, forwardly and rearwardly and this unit includes the rollers 32. The position of the rollers 32 forwardly or rearwardly relative to the arm 21 can be varied by adjusting the slide block 26 along the slide bracket 25.

As previously indicated, the crank arm 16 also actuates the arm 19. This arm 19 extends outwardly and downwardly and is pivotally supported adjacent its outer end by a vertical pivot 44 attached to the base plate 1. The outer end of this arm 19 is provided with an upstanding pin 45 which slides in a slot 46 formed in the forward end of the horizontal portion of a twisted link 75

47. The rear vertical portion of this link 47 is pivoted, as at 48, to the lower end of a clutch-actuating lever 49. This lever 49 is pivoted, as at 50, to an upstanding bracket plate 51 (Figure 1) for swinging movement forwardly and rearwardly in a vertical plane. The bracket 51 is attached to the horizontally extending vertically spaced supporting rods 52 which are supported by the forward and rearward walls of the housing portion 4. The bracket 51 is provided with a large opening 53 for preventing interference with the movement of the pivot pin 48. Furthermore, this bracket is provided with a pair of outwardly extending pins 54a which serve as stops to limit swinging movement of the lower end of lever 49. A tension spring 54 has its upper end connected to the pin 48 and its lower end anchored at 55 midway between the edges of the plate 51. This spring 54 serves as a snap-acting off-center mechanism for quickly moving the lower end of the lever from one side to the other into contact with one or the other of the stop pins 54a.

The upper end of the lever 49 is provided with a yoke 56 which straddles a clutch-actuating sleeve 57 which is slidably mounted on a horizontally disposed shaft 58 located adjacent the top of the portion 4 of the housing and supported by bearings 59 carried on the forward and rearward walls thereof. Each end of the sleeve 57 is provided with a clutch jaw 60. The rear clutch jaw 60 is adapted to cooperate with the clutch jaw carried by a sprocket 61 while the forward clutch jaw 60 is adapted to cooperate with a clutch jaw carried by the sprocket 62. Both of the sprockets 61 and 62 are rotatably mounted on the shaft 58. Adjacent sprocket 62 on shaft 58 is a sprocket 63 which is keyed thereon.

The sprocket 62 is driven by a chain 64 from the sprocket 10. The sprocket 61 is driven in a reverse direction by a chain 65 from a sprocket 66 which is keyed on a shaft 67 that parallels the shaft 58. This shaft 67 is supported by the bearings 68 carried by the forward and rearward walls of the housing portion 4. It will be noted that the sprocket 66 is adjacent the rear end of the shaft 67 and that this shaft carries adjacent its forward end a gear 69 which is keyed thereon and which is driven by the gear 11. The sprocket 63 drives a chain 70 which drives a sprocket 71 at the opposite side of the machine. This sprocket 71 is keyed on a horizontally disposed shaft 72 which is carried for rotation in a bearing bracket 73 that is attached to the forward wall of the housing portion 4. The shaft 72 extends forwardly through the forward wall of housing 4 and the shaft 58 similarly extends through the forward wall of the portion 4. The forward ends of these shafts carry crank arms 74 (Figures 2 and 4) which will actuate the toe-manipulating units 60 75 of the machine.

It will be apparent that the sprockets 63 and 71 will be driven in the same direction at all times when driven by the shaft 58. Furthermore, it will be apparent that this direction will be reversed upon alternate engagement of the forward clutch jaw 60 with the sprocket 61 and the forward clutch jaw 60 with the sprocket 62. This results in driving the shaft 58 in opposite directions. The clutch is alternately engaged to reverse the direction of the shaft 58 automatically by means of the rotation of the crank arm 16 which swings the actuating arm 19 about the pivot 44, and through link 47, swings the clutch-actuating lever 49 about the pivot 50, the spring 70 54 aiding in this movement and quickly snapping

the lower end of the lever into either its forward or rearward position in contact with either of the stops 54. Thus, during each rotation of the crank 16, rotation of the shaft 58 will be reversed.

The toe manipulating and gripping units 75 are illustrated best in Figures 1, 2 and 6. Each of these units comprises a plate 76 and a plate 77 which are horizontally disposed in spaced relationship. The plate 76 is provided with a depending flange 78 at its rear edge and the plate 77 is provided with an upstanding flange 79 at its rear edge which overlaps the flange 78. The horizontal part of the plate 77 is provided adjacent its rear edge with a pair of upstanding pins 79 which pass loosely through openings formed in the horizontal parts of the plate 76. Each of the plates 76 and 77 carries a cushion pad preferably of sponge rubber. It will be apparent that these pads can be adjusted towards or away from each other by moving plate 76 upwardly or downwardly on the pins 79. For moving the plate 76 and for retaining it in adjusted position, a spring handle member 81 is provided which has its ends normally contacting pins 79. A lifting force on this handle will spring its ends away from the pins 79. When the handle is released the ends thereof will again automatically contact the pins 79 and hold the plate 76 in adjusted position.

The unit 75 is carried by the outer end of the associated crank 74. It will be noted that the crank 74 is provided with a pin 81 which is rotatably mounted in an opening in the flange 79 and which passes through a vertical slot 82 in the flange 78. Rigidly secured to the flange 78 is the upper end of an upstanding arm 83. This arm 83 is provided with a bifurcated lower end 84 (Figure 1) which extends downwardly through a slot 85 in the top wall 22 of the housing portion 5. The bifurcated portion 84 cooperates with a small roller 86 carried by the housing 1. It will be apparent that the arm 83 will serve to prevent complete rotation of the unit 75 about the axis of the pin 81, and will thereby always maintain the unit upright, but will permit movement of the unit 75 in a circular path upon rotation of the crank 74. During this circular movement of unit 75, the arms 83 will move vertically and will oscillate about the roller 86.

In the use of this machine, the toes of both feet are inserted between the pairs of pads 80 of the units 75. The plates 76 are adjusted vertically to the proper extent to permit insertion of the toes and proper gripping thereof. The screw 29 is released and the block 26 is adjusted along the slide bracket 25 until the rollers 32 are properly located under the main arches and the screw 29 is again tightened to clamp the block 26 to the bracket 25. The machine is now properly adjusted and ready for operation.

When the motor 6 is started, the arm 21 will be reciprocated which will move the rollers 32 forwardly and rearwardly thereby rolling or kneading the arches. At the same time the arm 19 will be oscillated and will, consequently, swing the arm 49 which will alternately engage the clutch portions 60 to reverse the direction of rotation of the shaft 58. This will alternately and simultaneously reverse the path of movement of the units 75. The driving means is such that the units 75 will preferably travel through their circular paths a number of times while the rollers 32 are reciprocating once. For example, a ten to one ratio would be suitable. The action of

the machine in manipulating the foot is illustrated in Figure 7.

It will be apparent from the above description that I have provided a foot exercising machine having many desirable characteristics. Due to the fact that the toes are clamped by the units 75, which move in circular paths, and the arches are supported on the rollers 32, which reciprocate, while the heels are unsupported, a very natural manipulation of the feet will be obtained. Because the heel is unsupported, the patient can force his arches down onto the rollers 32 with the degree of pressure suitable for his particular case. The arch rolling or kneading action will, therefore, be accomplished with the degree of pressure selected by the patient.

Having thus described my invention, what I claim is:

1. A foot exercising machine comprising a toe gripping unit, a crank arm supporting said toe gripping unit and mounted for movement about a horizontal axis, a driving shaft for said crank arm, a reversing clutch for said shaft, an arch supporting unit spaced horizontally away from said toe gripping unit, a horizontally reciprocable slide carrying said arch supporting unit, a crank for reciprocating said slide, a driving shaft for said crank, a motor for driving both of said driving shafts, and means for controlling said reversing clutch by rotation of the slide actuating crank arm.

2. A foot exercising machine according to claim 1 wherein said slide is provided with adjustable means which carries said arch supporting unit so that said unit can be adjusted relative to said toe gripping unit.

3. A machine for exercising both feet simultaneously comprising toe gripping units supported in laterally spaced relationship, a crank arm supporting each of said toe gripping units and mounted for movement about a horizontal axis, a driving shaft for said crank arms, a reversing clutch for said shaft, a pair of arch supporting units spaced laterally from each other and in lateral alignment with said toe gripping units, said arch supporting units being spaced rearwardly of said toe gripping units, a horizontally reciprocable slide carrying both of said arch supporting units, a crank for reciprocating said slide, a driving shaft for said crank, a motor for driving both of said driving shafts, and a mechanical connection between the slide actuating crank and the reversible clutch for actuating said clutch in response to movement of said crank.

4. A foot exercising machine according to claim 3 wherein the slide embodies an arm connected to said slide actuating crank and a supporting structure carried by supporting rollers associated with guide tracks, said supporting structure being adjustable along said arm.

5. A machine according to claim 3 wherein pivots are provided between said crank arms and the toe gripping units so that the units will pivot about axes parallel to the horizontal crank axes, and means associated with said units for maintaining them substantially upright during rotation of said cranks which support them, said means comprising upstanding arms connected rigidly to said units and connected for rocking and vertical movement to a fixed support.

6. A machine for exercising both feet simultaneously comprising a pair of toe gripping units, a pair of units for supporting the arches of the feet while permitting the heel portions of the feet to remain substantially free, means for ad-

justing each toe gripping unit and its cooperating arch engaging unit relative to each other, means for moving both toe gripping units in circular paths in the same direction at the same speed and to the same extent, said last-named means automatically reversing the direction of movement at intervals, and means for reciprocating both arch supporting units in the same direction at the same speed and to the same extent towards and away from said toe gripping units.

7. A machine according to claim 6 wherein each of the arch supporting units comprises a roller mounted on the unit for movement about an axis transverse to the path of movement of said unit.

CHARLES C. MOSHIER. 15
